PROTECTOR FOR FRUIT BOXES

Reginald J. Clark, Boise, Idaho

Application October 18, 1941, Serial No. 415,658

1 Claim. (Cl. 217—3)

This invention relates to a protector for fruit boxes and other boxes, and has for one of its objects the production of a simple and efficient protector which may be cut from a single sheet of material and then folded to fit within the top of a box in a manner to protect the contents, such as fruit, from injury and also to hold the fruit in a proper position for display when the box is open.

A further object of this invention is the production of a simple and efficient protector for fruit and the like, which protector is provided with means for holding the protector within the upper end of the box.

Other objects and advantages of the present invention will appear throughout the following specification and claim.

In the drawings:

Figure 1 is a top plan view of a box showing the protector in place;

Figure 2 is a longitudinal sectional view taken on line 2—2 of Figure 1;

Figure 3 is a transverse sectional view taken on line 3—3 of Figure 1;

Figure 4 is a perspective view of one corner of the protector in a folded position;

Figure 5 is a plan view of the blank from which the protector may be formed;

Figure 6 is a plan view of the corner of a modified form of blank;

Figure 7 is a perspective view of a corner of the modified form of protector folded and in position;

Figure 8 is a top plan view of a further modified form of protector in position;

Figure 9 is a longitudinal sectional view taken on line 9—9 of Figure 8;

Figure 10 is a plan view of the blank from which the form shown in Figure 9 is formed;

Figure 11 is a perspective view of one corner of the blank shown in Figure 10; and

Figure 12 is a perspective view of the corner of a box showing one corner of the protector in position.

By referring to the drawings, it will be seen that 10 designates a box or container in which is mounted the protector 11 in the nature of a guard and the like, preferably formed of cardboard or other heavy paper which may be easily folded and at the same time provide a proper protecting medium for the fruit, vegetables, or other produce placed within the box 10. This protector 11 is preferably formed from a blank sheet of material comprising end flaps 12 and adjoining end collar portions 13, the inner edges 14 of which

are convex as shown. A pair of side flaps 15 is provided having inwardly extending convex edges 16. The end flaps 12 are adapted to be folded along the line 17 to extend at right angles to the collar portions 13 and the side flaps 15 are adapted to be bent along the lines 18 near their junction with the end collar portions 13, as shown clearly in Figure 5. The convex edges 16 are adapted to extend upwardly and the flaps 15 are adapted to be bent at right angles to the end collar portions 13 in the manner as shown in Figure 4, thereby providing a box-like protector or guard, the flaps 12 and 15 being adapted to fit snugly against the inner faces of the box and the end collar portions 13 being adapted to overlie the fruit, thereby protecting the fruit or other contents of the box 10.

The convex edges 16 of the flaps 15 are made of a contour to fit the average bulge or crown of fruit or other produce placed within the box. These flaps 15 are adapted to extend in a vertical position and to protect the sides of the fruit or contents of the box after the fruit is packed. The conventional lid 19 will flex to fit the crown or bulge of the fruit or contents of the box and will normally follow the contours of the convex edges 16. The contours of the edges 16 are made to fit the average bulge or crown and may in some instances be too low in which case the flaps would not quite reach the top of the fruit. If the flaps are too high they will project slightly above the lid of the box as the lid fits easily between the two side flaps when the side flaps are erect as will be obvious by considering Figure 3.

In actual practice the top layer of fruit in a box can be, and often is, protected from direct lid pressure by a suitable pad 19a of suitable material cut to fit the top of the box. The sides 15 of the protector which extend vertically protect the fruit and the fruit may slide down from the top edge of the box without injury, and these sides 15 will protect the exposed portions of the fruit from outside sources where the crown of the fruit extends above the upper edge of the box.

As shown in Figures 6 and 7, the blank 11a may be provided with supporting ears or tongues 20 at the corners of the blank adjacent the ends of the side flaps 15a and the end flaps 12a which ears or tongues 20 may rest upon the end cleats 21 of the box 10a, as shown in Figure 7, to support the protector or guard in proper position and prevent the protector from slipping down into the box. In the type shown in Figure 7, the protector may be supported flush with the upper edge of the box and the tongues or ears 20 will provide means to

hold the protector from dropping down into the box while the fruit is being packed, and this protector is especially designed for that type of box having the end cleats 21 described above.

It has been found in actual practice that the first layer or two of fruit or other produce, may be packed in the box and then the protector may be installed and the fruit already in the box will prevent the protector from dropping lower than the protector should be, or in other words, the fruit will hold the protector in the position shown in Figure 2 before the lid 19 is placed in position.

An important feature of the present invention is the fact that the end collar portions 13 of the blank are hinged or folded, as at 18, to the side flaps 15 as shown and described, and this may be accomplished by scoring, creasing, or providing any type of fold common to the trade. The sides 15 preferably stand straight up and project sufficiently above the top edge of the box to protect the bulge and permit the two end collar portions 13 to lie out over the fruit in a substantially horizontal manner such as is shown in Figure 2, since these end collar portions 13 extend substantially horizontally over the fruit, these portions providing positive protection against the fruit cutting against the top edge or end of the box and protecting the fruit from becoming bruised by the lid when pressure is applied in the nailing process. The fruit, before the lid is applied is actually an inch or so higher than the top edge of the box all around so that when pressure is applied to the lid at the ends the fruit is forced down tighter in the box until the ends of the lid and the ends of the box meet, at which time the lid is nailed to the box. Since the pressure is applied entirely at the ends of the lid, the fruit in the center of the box slides down only a short distance and thus the bulge is formed. The horizontal or end collar portions 13 which extend over the fruit at the ends of the box may contain printed matter or various designs, if desired, so that when the box is opened an advertising medium may be provided as well as a protector. Suitable subject matter may be printed upon each end collar portion 13 without departing from the spirit of the invention.

As shown in Figures 8 to 11, inclusive, there is illustrated a modified type of the invention wherein a protector 22 is illustrated and is formed from a blank sheet of material comprising end flaps 23 and side flaps 24. Each end flap is adapted to be bent along the line 25 to provide the substantially horizontal and collar portion 26 which is adapted to protect the fruit at each end of the box. Horizontally extending tongues or ears 27 are provided at the junction between the side flaps 24 and end flaps 23, and these tongues or ears 27 are adapted to overhang the

ends 28 of the box 29, in the manner shown in Figures 8, 9 and 12. These tongues or ears 27 are adapted to hold the protector in place upon the box and to prevent the protector from dropping down into the box. The side flaps 24 are adapted to extend vertically when placed in the box so that the upper edge 30 of the side flaps 24 may extend upwardly. The cover or lid is adapted to be secured to the ends 28 of the box and is adapted to flex to follow the contour of the upper convex edge 30, but because of the fact that the protector is formed of cardboard and the like, these side flaps 24 and their upper edges 30 may be folded inwardly under the pressure of the lid, at the same time protecting the fruit or other contents of the box along the sides of the box.

It will be noted from Figure 12 that the end flaps 23 are adapted to fit snugly against the inner faces of the ends of the box and the collar portions 26 are adapted to extend in a substantially horizontal position overhanging the contents of the box at the ends of the box. The side flaps 24 are adapted to fit snugly against the inner faces of the sides of the box and extend vertically thereof. In this way the fruit or contents of the box will be protected around all four side edges of the box, that is to say at the ends and also along each side for the full height of the bulge of the fruit toward the center of the box.

It should be understood that certain detail changes may be employed without departing from the spirit of the invention, so long as such changes fall within the scope of the appended claim.

Having described the invention, what I claim as new is:

A fruit guard comprising a flexible sheet having a central opening, fruit-protecting collar portions carried by the guard at opposite ends of said central opening, side and end flaps bent at substantially right angles to the collar portions said flaps being adapted to fit snugly against the inner faces of the side and end walls of a container with which the guard is used, and projecting supporting tongues carried by the side flaps and in the plane thereof intermediate the side and end flaps, each tongue having an upper edge extending in a substantially horizontal plane, the collars being substantially flush with the upper edges of the tongues, the tongues having lower edges parallel to the upper edges of the tongues and being adapted to rest upon portions of a container with which the guard is used for supporting the guard in position and preventing the guard from dropping down into the container.
